United States Patent [19]

Kosako et al.

[11] Patent Number: Des. 313,618

[45] Date of Patent: ** Jan. 8, 1991

[54] FEEDER FOR ELECTRONIC COPYING MACHINE

D. 295,532 5/1988 Kosako D18/42

[75] Inventors: Mikio Kosako; Ritsuko Makihara; Yoichi Tatsuta, all of Osaka, Japan

OTHER PUBLICATIONS

The Office; Jul. 1985; p. 79; Mita #DC-5132; lower left side; Original in Scientific Library.

[73] Assignee: Sharp Corporation, Osaka, Japan

Primary Examiner—Nelson C. Holtje

Assistant Examiner—Caron D. Veynar

Attorney, Agent, or Firm—Flehr, Hohbach, Test, Albritton & Herbert

[**] Term: 14 Years

[57] CLAIM

[21] Appl. No.: 44,453

The ornamental design for a feeder for electronic copying machine, as shown and described.

[22] Filed: Apr. 30, 1987

DESCRIPTION

[30] Foreign Application Priority Data

Nov. 5, 1986 [JP] Japan 61-43761

[52] U.S. Cl. D18/42

[58] Field of Search D18/36-44; 271/3, 3.1, 8.1, 9; 355/200, 308, 309; 358/498

FIG. 1 is a top plan view of the feeder for electronic copying machine showing our new design;
